ELECTRIC SWITCH

Hans Jonas, Dortmund, Germany

Application April 12, 1932, Serial No. 604,706
In Germany April 15, 1931

12 Claims. (Cl. 200—43)

My invention relates to electric switches adapted for use in electric circuits for protecting them against unauthorized use.

In lighting plants, electric motors, door-locks and other devices and especially in motor cars the unauthorized use is prevented by electric circuits putting optical or acoustical signals into operation, if they are closed or interrupted by unauthorized persons.

10 The object of my invention is to render a signal operative upon alteration of a normal electric circuit.

To these ends my invention consists in an apparatus constructed and operating as hereinafter fully described and particularly pointed out in the claims.

Referring to the drawing in which like letters designate like parts in the several views, Figure 1 is a cross section of the electric switch, the movable rings separated from the body, Figure 2 is an elevation of the inner face of one of the movable rings forming the upper parts of the switch, Figure 3 is a cross section of the ring shown in Figure 2, Figure 4 is a top plan view of the switch, and Figure 5 is a wiring diagram.

In the drawing wherein a selected embodiment of my invention is illustrated, *v* indicates a stepped pyramidal stationary element or body made of insulating material. This element includes a base 9 and a vertical wall 10 extends upwardly from this base 9 and is spaced from the periphery thereof thereby providing a peripheral flange 11. At the upper end of the wall 10 is an inwardly extending horizontal wall 12 which terminates in a vertical wall 13. An inwardly projecting horizontal wall 14 extends inwardly from the upper end of the wall 13 and terminates in a vertically extending wall 15. A top 16 at the upper end of the wall 15 encloses the area bounded by said wall. The outer surface of the body is therefore stepped and provides surfaces on which ring-shaped contactors are rotatably mounted.

One of the ring-shaped contactors 17 includes a vertical wall 18 and a horizontal wall 19. The lower end of the vertical wall 18 is adapted to rest on the top of the flange 11 and the inner surface of this wall is adapted to ride over the outer surface of the vertical wall 10. The bottom surface of the horizontal wall 19 is adapted to rest on the top surface of the wall 12. The inner part of the top surface of the wall 19 is recessed at 20 to receive the lower end of the vertical wall 21 of the contactor 22. The inner surface of the wall 21 is adapted to ride on the outer surface of the wall 13. The contactor 22 includes a horizontal wall 23

which is adapted to ride on the top surface of the wall 14. The inner part of the top surface of the wall 23 is recessed as at 24 to receive the lower end of the vertical wall 25 of the contactor 26 and the inner surface of this wall 25 rides on the outer surface of the wall 15. The contactor 26 includes a horizontal wall 27 which rests on the top 16. The contactors 17, 22 and 26 are L-shaped in cross section and, as described, they rest on the steps of the stepped pyramidal element *v* to be rotatable thereon and by disposing the lower ends of the walls 21 and 25 respectively in the recesses 20 and 24, these rings are interclocked.

An axle or pivot *k* projects through medially located openings in the top plate 27 and the top 16 and through a similarly located opening in the base 9 and the lower end is screw-threaded so that the head of the pivot *k* may be urged into tight engagement with the top 27, and since the contactors are interlocked and are interengaged with the steps on the pyramidal element *v* these parts are interlocked together. The contactors, which as a whole are indicated by *r*, are equipped with contact strips *t* and *t'*. The contact strips *t* are respectively mounted on the lower surfaces of the horizontal walls 19, 23 and 27 in juxtaposition to the vertical walls of the respective contactors *r*. The contact strips *t'* are respectively mounted on the inner surfaces of the vertical walls 18, 21 and 25 of the contactors *r*.

The contact strips *t* are adapted to respectively cooperate with pairs of contacts *s* to close the circuit between the contacts of each pair when moved into bridging relation therewith, and these pairs of contacts are respectively mounted in the horizontal walls 12, 14 and 16 adjacent the vertical walls extending upwardly thereinto. The contact strips *t'* are respectively adapted to cooperate with pairs of contacts *s'* to close the circuit between the contacts of each pair as the strips *t'* move into bridging relation with the respective pairs of contacts *s'*. Preferably, the pairs of contacts *s* are arranged in alignment with each other as are the pairs of contacts *s'* and in the illustrated embodiment 100 of the invention the respective pairs of contacts *s* are mounted in the element *v* in diametrical relation with the pairs of contacts *s'*.

As shown best in Fig. 2, the contact strips *t'* are of a length slightly less than the length 105 of the inner periphery of the contactor on which they are mounted, the ends being spaced apart. The contact strips *t* are relatively short and are mounted in the contactors *r* in diametrical opposition to the spaces between the ends of the 110

contact strips t' and the contactors t are of a length equal to the spaces between the ends of the contact strips t' and consequently the ends of the contacts t on each contactor are aligned 5 with the ends of the contact t' on that contactor.

The relative situation of the pins s and the pins s' can be chosen at will but then, of course, the metal strips t and t' must be placed accordingly. The upper outer surfaces of the rings r 10 are provided with letters or figures as shown in Figure 4.

The switch controls two electric circuits one of which includes the optical or acoustical signal and the other of which is the normal or main 15 circuit. The device is arranged so that, when a certain predetermined combination of numbers on the three rings r are arranged in alignment with a predetermined position, the normal circuit is closed for at this time the three strips t close 20 the circuit between the respective pairs of pins s , which are connected in series, and, when the parts are so arranged in an electric circuit, such as that shown in Figure 5, circuit is closed from the battery 1 through conductor 2, conductor 3, 25 the ignition coil 4 of an automotive engine or other device in the normal circuit to be controlled by the contacts s and strips t . From coil 4 current flows through conductor a to the pairs of contacts s and when circuit therebetween is 30 closed by the strips t , current flows to the conductor b and thence through conductor 5 to ground. One terminal of the battery 1 is grounded as indicated at 6.

So long as the three rings are arranged with 35 the predetermined numbers in alignment, the foregoing circuit is closed. However, when one of the rings r is moved sufficiently to disengage the strip t thereon from the pair of pins s co-operating therewith, the strip t' on this ring 40 closes the circuit between the pair of pins s' co-operating therewith. Since the pairs of pins s are connected in series, disengagement of a strip t from any pair of contacts s opens the circuit. The pairs of pins s' are connected in parallel and hence if only one of the rings r is moved, 45 the circuit will be closed and likewise if two or more rings are moved the circuit will be closed.

The circuit, including the pins s' has additional switches therein which may be, for example, 50 located at suitable places in an automotive vehicle such as in the door, or in connection with the brake, or in connection with the hood, or at other suitable places on the vehicle. Such switches are indicated by i and if, for example, 55 one of these switches is located in the door, it will be arranged to be open so long as the door remains closed. However, when the door is opened, the switch i associated therewith is closed and if the circuit is at this time closed between 60 a pair of pins s' by a strip t' , the signal 9 which may be, for example, the horn of the automobile, is rendered operative. The switches i like the pairs of pins s' are connected in parallel.

When one of the switches i is closed and the 65 circuit between a pair of pins s' is closed, the signal 9 is rendered operative, current flowing from the battery 1 through conductor 2, conductor 7, signal 9, conductor 8, one or more of the switches i , conductor c , one or more of the 70 pairs of pins s' connected by the respective strips t' , conductor b , through conductor 5 to ground.

The switch may be used in connection with the lighting plant and, when this is done, the pairs of pins s and the metal strips t cooperat- 75 ing therewith control the electric circuit to the

lamps or other devices operated by the plant. Under these conditions, the pairs of pins s' and the metal strips t' control the circuit to a suitable signal. When the circuit to the lamps is interrupted, the circuit to the signal is closed 80 when the switch is used under such conditions.

It is to be understood that the switches i might be eliminated so that the signal would be rendered operative as soon as the circuit through the respective pairs of pins s is interrupted. 85

It will be obvious that my device may be used in different ways without departing from the spirit of my invention. The number of rings, the metal pieces in the rings, the shape and form of the contact pins, all these may be changed in any desired manner according to the use for which my switch is wanted. Of course, the switch can be arranged for more than two circuits if desired, and I do not intend to be limited to the exact details shown. 90

What I claim is:

1. In a switch of the class described, a stepped body, a pair of contacts projecting from a horizontal surface of the stepped body, another pair of contacts projecting from a vertical surface 100 of the stepped body and spaced from the first pair of contacts, a rotatable member mounted on said body and including a horizontal part and a vertical part adapted to respectively co-operate with the horizontal and vertical surfaces 105 of the stepped body, a contact strip on the horizontal part of said rotatable member and adapted to cooperate with the pair of contacts projecting from the horizontal surface of said body, another contact strip mounted on the vertical part 110 of said rotatable member and adapted to co-operate with the pair of contacts projecting from the vertical surface of said body, the adjacent ends of said contact strips being in substantial alignment one with the other to provide a continuous contact on said rotatable member whereby one of said contact strips disengages the pair of contacts cooperating therewith upon rotation of said rotatable member relative to said body as the other of the contact strips engages the 115 pair of contacts cooperating therewith.

2. In a switch of the class described, a stepped body, independent pairs of contacts projecting from the horizontal surfaces of the stepped body, other independent pairs of contacts projecting 120 from the vertical surfaces of the stepped body and spaced from the first pairs of contacts, independently rotatable members of substantially L-shaped cross section and respectively mounted on the steps of said body, means securing said 125 rotatable members on said stepped body for independent rotation thereon, contact strips in said rotatable members and adapted to respectively cooperate with said pairs of contacts, the adjacent ends of the contact strips in each of 130 said members being in substantial alignment one with the other to provide a continuous contact on each of said rotatable members whereby one of said contact strips disengages the pair of contacts cooperating therewith upon rotation of the 135 rotatable member in which it is mounted relative to said body as the other of the contact strips in said rotatable member engages the pair of contacts cooperating therewith.

3. In a switch of the class described, a stepped body, independent pairs of contacts projecting from the horizontal surfaces of the stepped body, other independent pairs of contacts projecting from the vertical surfaces of the stepped body and spaced from the first pair of contacts, inde- 140

- pendently rotatable members mounted on the steps of said body, contact strips in said rotatable members and adapted to respectively cooperate with said pairs of contacts, the adjacent 5 ends of the contact strips in each of said members being in substantial alignment one with the other whereby one of said contact strips disengages the pair of contacts cooperating therewith upon rotation of the rotatable member in which it is mounted relative to said body as the other 10 of the contact strips in said rotatable member engages the pair of contacts cooperating therewith, each of said rotatable members having identifying indicia thereon positioned relative to the contact strips therein whereby the alignment 15 of predetermined of the indicia on said rotatable members locates the contact strips on said rotatable members in predetermined positions relative to said pairs of contacts, each of said rotatable 20 members being substantially L-shaped in cross section and including horizontal and vertical parts respectively cooperating with the horizontal and vertical surfaces of the stepped body, said rotatable members including interengaging parts, 25 and means securing said rotatable members on said stepped body for independent rotation thereon.
4. In a switch of the class described, a stepped body, independent pairs of contacts projecting from the horizontal surfaces of the stepped body, other independent pairs of contacts projecting from the vertical surfaces of the stepped body and spaced from the first pair of contacts, means connecting the pairs of contacts projecting from 30 one set of corresponding surfaces on the stepped body in series in an electric circuit, other means connecting the pairs of contacts projecting from the other of the sets of corresponding surfaces on the stepped body in parallel in an electric 35 circuit, independently rotatable members mounted on the steps of said body, contact strips in said rotatable members and adapted to respectively cooperate with said pairs of contacts, the adjacent ends of the contact strips in each of 40 said members being in substantial alignment one with the other whereby when one of the contact strips cooperating with a pair of contacts of the pairs of contacts connected in series 45 disengages the pair of contacts cooperating therewith upon rotation of the rotatable member in which said contact strip is mounted the circuit through the pairs of contacts connected in series 50 will be opened as the other of the contact strips mounted in said rotatable member engages the pair of contacts cooperating therewith and closes 55 circuit therebetween to close the circuit including the contacts connected in parallel, each of said rotatable members being substantially L-shaped in cross section and including horizontal 60 and vertical parts respectively cooperating with the horizontal and vertical surfaces of the stepped body, said rotatable members including interengaging parts, and means securing 65 said rotatable members on said stepped body for independent rotation thereon.
5. In a switch of the class described, a cylindrical pyramidal stepped body, ring contactors respectively mounted on the steps of said body, each of said ring contactors and the step of the body with which it cooperates having circuit controlling means, and means for securing said ring contactors on said body and in said engagement 70 with each other to permit rotation of said ring contactors independently of each other whereby said ring contactors may be moved relative to said body to determine the operation of the respective circuit controlling means.
6. In a switch of the class described, a cylindrical pyramidal stepped body, ring contactors respectively mounted on the steps of said body and successively engaged with each other, each of said ring contactors and the step of the body with which it cooperates having circuit controlling means, and means for securing said ring contactors on said body and in said engagement 75 with each other to permit rotation of said ring contactors independently of each other whereby said ring contactors may be moved relative to said body to determine the operation of the respective circuit controlling means.
7. In a switch of the class described, a cylindrical pyramidal stepped body, ring contactors respectively mounted on the steps of said body, each of said ring contactors and the step of the body with which it cooperates having circuit controlling means, means connecting the respective circuit controlling means in series, and means for securing said ring contactors on said body for rotation thereabout independently of each other whereby rotation of any one of said contactors 80 may affect the electric circuit in which said circuit controlling means are connected.
8. In a switch of the class described, a cylindrical pyramidal stepped body, ring contactors respectively mounted on the steps of said body, each of said ring contactors and the step of the body with which it cooperates having independent circuit controlling means, and means for securing said ring contactors on said body for rotation thereabout independently of each other, 85 the circuit controlling means associated with each of said contactors and the step with which it cooperates being positioned relative to each other so that circuit is closed through one of said circuit controlling means and opened through the other of said circuit controlling means when said ring contactors are respectively moved relative to said body.
9. In a switch of the class described, a cylindrical pyramidal stepped body, ring contactors respectively mounted on the steps of said body, each of said ring contactors and the step of the body with which it cooperates having independent circuit controlling means, means connecting corresponding of the respective circuit controlling means in series in an electric circuit, means connecting the other of the respective circuit controlling means in parallel in an electric circuit, and means for securing said ring contactors on said body for rotation thereabout independently 100 of each other, the respective contact means on each of said ring contactors being positioned relative to each other so that rotation of any one of said ring contactors will open or close the circuit through the contactors connected in series 105 and at the same time oppositely affect the circuit in which the cooperating contact means is included.
10. In a switch of the class described, a cylindrical pyramidal stepped body, a ring contactor including vertically and horizontally extending parts respectively engaged with the vertically and horizontally extending parts of the lowermost step of said body, another ring contactor including vertically and horizontally extending parts 110 and having said parts respectively engaged with the vertically and horizontally extending parts of the next adjacent step of said body and having the lower end of the vertical part thereof rested 115 on the horizontally extending part of the ring 120

- contactor on the lowermost step of said body, and means cooperating with the upper of said ring contactors to retain said ring contactors on said body to permit rotation of said ring contactors relative to said body, each of said ring contactors and the step of the body with which it is engaged including circuit controlling means adapted to be operated by rotation of said ring contactor relative to said body.
- 10 11. In a switch of the class described, a cylindrical pyramidal stepped body, a ring contactor including vertically and horizontally extending parts respectively engaged with the vertically and horizontally extending parts of the lowermost step of said body, another ring contactor including vertically and horizontally extending parts and having said parts respectively engaged with the vertically and horizontally extending parts of the next adjacent step of said body and having the lower end of the vertical part thereof rested on the horizontally extending part of the ring contactor on the lowermost step of said body, means cooperating with the upper of said ring contactors to retain said ring contactors on said body to permit rotation of said ring contactors relative to said body, each of said ring contactors having a pair of contact strips thereon electrically separated from each other by providing a continuous contact surface, each of said steps having independent contact means thereon respectively adapted for cooperation with the contact strips on the ring contactor cooperating with the respective step whereby rotation of each of said ring contactors may disengage one of the contact strips thereon from the contacts cooperating therewith and simultaneously engage the other of the contact strips thereon with the contacts cooperating therewith. 105
